SAFETY RAZOR

Joseph Rice, Chicago, Ill.

Application October 24, 1932, Serial No. 639,202

2 Claims. (Cl. 30—96)

My invention relates to safety razors and more particularly to a novel device used in combination with the ordinary safety razor having a backing member, a guard, and a blade clamped between the guard and the backing member.

My invention contemplates the provision in this combination of a cushioning sheet interposed between the backing member and a blade, this sheet being adapted to act as a cushion to equalize the blade pressure at all points. The cushioning sheets may be employed on both sides of the blade or on one side only although I find the best results to be obtained when it is used on both sides as shown in Fig. 1.

15 I will describe the preferred form of the invention by reference to the accompanying drawing wherein—

Fig. 1 is a transverse sectional view through a razor of a well known type showing the application 20 of my invention thereto;

Fig. 2 is an enlarged sectional view at the line 2—2 of Fig. 1;

Fig. 3 is a plan view of the cushioning sheet removed from the razor.

25 Referring now in detail to the drawing, I show in Fig. 1 a razor having a handle 5, a guard 6, and a backing member 7. As is usual in this type of razor, the backing member 7 has a projecting stud 8 which is screw-threaded into the handle 5 so as to clamp the guard 6 down against the blade 9. I have shown interposed on the opposite sides of the blade the two cushioning sheets 10 and 11 which, it will be noted, terminate substantially at the edge of the backing member 7 and which 30 cover substantially all of the surface of the backing member that is engaged by the blade. The manner of applying the cushioning sheets, it is believed, will be obvious as they are simply cut out and placed into position. These cushioning sheets, however, produce an entirely unexpected 35 and unusual result in connection with the razor. They may be made of any suitable type of material—such for example as paper, cork, asbestos, a soft metal such as tinfoil, and in fact any material 40 which will act as a cushion between hard razor blade surface and the hard backing member surface. I preferably use paper both for the sake of economy and because it is water absorbent, and, when it becomes soaked with water, produces 45 an additional cushioning action which would not otherwise be obtained.

50 Referring now to Fig. 2, I have illustrated a greatly enlarged view of the edge of the razor where the backing member 7, cushioning members 10 and 11, and the blade 9 are seen from the

side. One of the difficulties encountered with a razor blade is to get the backing member to have a smooth surface at the edge. I have illustrated at 12 and 13 the results of the razor backing member being dropped or of being poorly finished in the first place. These depressions and bumps at the edge would, if the razor blade were pressed against them, cause distortion at the edge of the blade so that instead of extending in a direct plane it would be distorted out of shape. Naturally such a condition does not make for proper 5 shaving.

By employing the yielding cushion sheets 10 and 11, which are much softer than the backing member or the blade, most of these irregularities 15 are taken up in the cushioning member and thus the edge of the razor blade is held more nearly in a straight line; in fact, the cushioning members 10 and 11 act as shims to take up the unevenness of both the guard and the backing member to 20 thus equalize the blade pressure so that it will maintain its normal straight edge after being clamped in the razor.

When the cushion sheet made of paper becomes 25 wet, it acts further as a hydraulic shock absorber to prevent the edge of the blade from vibrating as it has a tendency to do. The yielding action of the sheets also help to hold the blade in its set position and allows for greater latitude in adjusting the clamping force by screw threads connecting the handle and the member 8.

It is obvious, of course, that the invention is not limited to the particular type of razor shown as it may be used in various other types equally as well.

35 I find that due to the equalizing effect of these cushioning sheets there is much less danger of cutting the face than without such sheets. This is no doubt due to the fact that the edge of the blade is held more nearly straight and also because the blade is not solidly backed up and, therefore, may yield away from a rigid obstruction.

Having thus described my invention, what I 40 claim as new and desire to secure by Letters Patent is:

1. In a razor the combination with a blade of a backing member and a guard member therefor, together with a shim clamped between the backing member and the blade, said shim being constructed of water absorbent paper so that when the razor is wet the water in the paper acts to 45 prevent vibration of the blade, said shim having its side edges terminating short of the blade edges and substantially even with the side edges 50 55

of the backing member whereby to expose the cutting edges of the razor blade for the shaving operation.

2. In a razor the combination with a blade of a backing member and a guard member therefor, together with shims of yieldable material clamped between the members and the blade to even out the clamping tension on the blade, the

material of said shims being water absorbent, the side edges of the shims terminating short of the blade edges so as not to obstruct the cutting by the blade edges, the shim between the backing member and the blade being completely covered by the backing member.

JOSEPH RICE.
